UNITED STATES PATENT OFFICE.

CHARLES T. WESTLAKE, OF ST. LOUIS, MISSOURI, ASSIGNOR TO CAST STEEL PILOT COMPANY, OF ST. LOUIS, MISSOURI, A CORPORATION OF DELAWARE.

BLANK FOR MAKING LOCOMOTIVE-PILOTS.

1,178,114.

Specification of Letters Patent.

Patented Apr. 4, 1916.

Application filed June 24, 1915. Serial No. 36,076.

To all whom it may concern:

Be it known that I, CHARLES T. WESTLAKE, a citizen of the United States, residing at St. Louis, Missouri, have invented a certain new and useful Improvement in Blanks for Making Locomotive-Pilots, of which the following is a full, clear, and exact description, such as will enable others skilled in the art to which it appertains to make and use the same, reference being had to the accompanying drawings, forming part of this specification.

My invention relates generally to locomotive pilots and more particularly to a blank or flat skeleton frame which is adapted to be bent at various points and along certain lines so as to produce a pilot of the desired conformation.

The principal object of my invention is to produce a blank which is particularly designed for a locomotive pilot, said blank being stamped, or cut from a plate or section of comparatively heavy sheet metal, and said blank having certain portions bent to form reinforcing ribs and flanges, and which latter are effective in imparting to the finished pilot the requisite strength and rigidity.

A further object of my invention is to provide a one piece blank adapted to be bent to form a locomotive pilot, such one piece construction being advantageous in that it is entirely devoid of joints, rivets, bolts and like attaching and fastening device.

With the foregoing and other objects in view, my invention consists in certain novel features of construction and arrangement of parts, hereinafter more fully described, claimed and shown in the accompanying drawings, in which—

In the drawings—Figure 1 is a plan view of a blank which is cut from a section of sheet metal, said blank being of the contour to form a locomotive pilot in accordance with my invention. Fig. 2 is a plan view of a pilot which is produced with a blank of my improved construction. Fig. 3 is a side elevational view of the pilot. Fig. 4 is an enlarged detail section taken approximately on the line 4—4 of Fig. 1. Fig. 5 is an enlarged sectional view taken approximately on the line 5—5 of Fig. 1.

In producing a locomotive pilot with my improved blank, I first cut or stamp with

suitable dies or otherwise from a section of 55 sheet metal such as steel plate, a blank 10 which is bilaterally symmetrical and which is of the proper contour to produce the finished pilot when the blank is later pressed to proper shape. The bilateral portions of 60 the blank are inclined with respect to each other and their lower edges 11 are straight and meet at a central point, which latter forms the apex or nose of the pilot when the same is finished. Formed at the outer 65 forward ends of the blank are projecting portions 12, preferably triangular in outline, the same serving as steps when the blank is pressed to proper shape. The side edges 13 of the blank are inclined with respect 70 to each other and also with respect to the axis or medial line of the blank, and formed integral with or projecting outwardly from the side edges are members 14 which, when the blank is bent to proper shape, serve as 75 brackets which engage beneath the beam to which the finished pilot is applied. The upper central portion of the blank is cut away as designated by 15 in order to form a 80 pocket or space which receives the coupler head of the locomotive to which the finished pilot is applied. The upper edges 16 of the blank to the sides of central opening are arranged substantially at right angles to the side edges 13 and said upper edges are 85 inclined with respect to the medial line of the blank. Projecting outwardly from the corners of the blank between the side edges 13 and upper edges 16 and from the corners between said upper edges 16 and the central 90 opening 15 are sections 17 which, when the blank is bent to proper form, serve as attaching plates or brackets which engage the beam to which the pilot is applied. After the blank having the contour substantially 95 as herein described is produced it is placed in a suitable press to form a practically continuous marginal bead 18, the same extending along the edges 11, along the edges of the extensions 12, along the side edges 13, along the top edges 16 and along the edges of the opening 15. This bead is preferably 100 formed by slightly rounding or curving the metal adjacent to the edges of the blank as shown in Fig. 5, although, if desired, said bead may take the form of a flange extending either forwardly or rearwardly from the main body portion of the blank. The cen-

tral portions of the extensions 17 are preferably embossed or pressed upwardly so as to occupy substantially the same plane with the upper portion of the bead 18, such embossing being designated by the numeral 19. After the blank has thus been beaded and embossed, it is placed in a suitable die or punch-press and elongated sections of material are punched or cut from the body of the blank to form a series of elongated openings or slots 20, the same being substantially parallel with each other and likewise substantially parallel with the side edges 13. At the time these slots are punched or formed, the material in the blank adjacent to the edges of said slots is bent rearwardly as designated by 21, thereby forming reinforcing ribs or flanges at the sides of said slots and when the blank is bent to proper shape, the portions of material between said slots serve as pilot bars or slats 22. The extensions 12 are now bent upwardly at an angle with respect to the plane occupied by the body of the blank and if desired, the upper faces of these projections can be corrugated or roughened, thus providing tread gripping surfaces for the boots or shoes of the trainmen. The upper portions of the side extensions 14 are now bent downwardly or rearwardly along the dotted lines *a* Fig. 1 until they occupy positions substantially at right angles to the main body portions of said extensions, after which the latter are bent downward or rearward along the dotted lines *b*, Fig. 1 until they occupy positions substantially at right angles to the plane occupied by the body of the blank, and thus said extensions serve as brackets to engage beneath the beam to which the finished pilot is applied. The blank is now placed in a suitable press or bulldozer and bent to proper shape and in so doing the bilateral portions of the blank are bent rearwardly with respect to the medial line so that said bilateral portions occupy inclined positions with respect to each other and with respect to a vertical plane and as this is done, the side edges 13 are brought into substantially vertical positions and the upper edges 16 are brought into position so that they occupy a substantially horizontal line. Either before or after this final bending of the blank to shape, the extensions 17 are bent upward slightly so that they occupy a plane at an angle relative to the plane occupied by the body of the blank, and thus when the pilot is finished these extensions occupy a substantially vertical plane and

bear directly against the front face of the beam to which the pilot is applied.

The blank of my improved construction is comparatively simple, can be easily and cheaply produced, is entirely devoid of joints, and therefore, does away with the time and labor involved in the setting of rivets and like fastening devices, and when the blank is bent to proper shape, a locomotive pilot is produced which, while comparatively light in weight, has the requisite strength and rigidity.

I claim:

1. A blank for making locomotive pilots comprising a flat metal plate of polygonal shape, the bilateral portions of which plate are symmetrical, the corresponding top, side and bottom edges of which bilateral portions diverge, there being slots formed in said blank, which slots are substantially parallel with each other and with the side edges of said blank, and portions of the outer edges of said blank and portions of the edges adjacent to said slots being bent to form reinforcing elements.

2. A blank for making locomotive pilots comprising a flat metal plate of polygonal shape, the bilateral portions of which plate are symmetrical, the corresponding top, side and bottom edges of which bilateral portions diverge, there being slots formed in said blank, which slots are substantially parallel with each other and with the side edges of said blank, and extensions on said blank, which extensions are adapted to be bent to form attaching brackets when said blank is bent to the desired finished conformation.

3. A blank for making locomotive pilots comprising a flat metal plate of polygonal shape, the bilateral portions of which plate are symmetrical, the corresponding top, side and bottom edges of which bilateral portions diverge, there being slots formed in said blank, which slots are substantially parallel with each other and with the side edges of said blank, and extensions on the ends of said blank, which extensions are bent to form steps when the blank is bent to the desired finished conformation.

In testimony whereof I hereunto affix my signature in the presence of two witnesses, this 21st day of May, 1915.

CHARLES T. WESTLAKE.
